UNITED STATES PATENT OFFICE.

JOSEPH F. BUHR, OF DETROIT, MICHIGAN.

MULTIPLE DRILL HEAD.

Application filed December 6, 1920. Serial No. 428,565.

To all whom it may concern:

Be it known that I, JOSEPH F. BUHR, a citizen of the United States of America, residing at Detroit, in the county of Wayne 5 and State of Michigan, have invented certain new and useful Improvements in Multiple Drill Heads, of which the following is a specification, reference being had therein to the accompanying drawings.

10 This invention relates to a multiple drill head and has special reference to that class of drill heads having a multiplicity of adjustable drills, bits or other boring instrumentalities that may be operated in synchronism from a single master driven spindle.

20 My invention aims to provide a multiple drill head embodying transmission housings and socket members, the transmission housings being adjustable relative to the power transmission mechanism and the socket members adjustable relative to the transmission housings. It is therefore possible to position the socket members in any 25 desired relation relative to one another within the limits of the drill head and by such an arrangement a piece of work may be expeditiously and economically operated upon with absolute accuracy.

30 My invention also aims to provide a multiple drill head having adjustable transmission housings and socket members wherein provision is made for maintaining a lubricant in said transmission housings and the 35 socket members to insure ease of operation without waste of lubricant due to any adjustments of the transmission housings and socket members.

40 The above and other results are attained by a mechanical construction which has been put into practice and found satisfactory, and this construction has been shown in the accompanying drawings, wherein

45 Figure 1 is a bottom plan of the multiple drill head;

Fig. 2 is a horizontal sectional view of the drill head on a smaller scale; showing the power transmission mechanism;

50 Fig. 3 is a similar view on a larger scale showing the transmission housings;

Fig. 4 is a vertical sectional view of a portion of the drill head taken on or about the line IV—IV of Fig. 2;

55 Fig. 5 is a vertical sectional view of a modified form of adapter for the drill head, and,

Fig. 6 is a similar view of a further modified form of adapter.

Reference will first be had to Fig. 4 showing the preferred form of adapter in connection with the drill head and the reference numeral 1 denotes a sleeve member adapted to form part of a drilling machine, the sleeve member being arranged for vertical adjustment so that a drill head supported therefrom may be raised and lowered relative to a piece of work. The lower end of the sleeve member has an integral flange 2 and adjustable against said flange and centered by the lower end of the sleeve member 1 is a transition casing 3 which is adapted to be fixed relative to the flange 2 by clamping members 4 attached to the casing 3 by screw bolts 5 or other fastening means, said clamping members overhanging the flange 2 and adapted to be clamped in engagement therewith when the screw bolts 5 are tightened.

The transmission casing 3 has its lower end provided with a flange 6 and connected to said flange by screw bolts 7 or other fastening means is a cylindrical drill head 8 provided with a top wall 9 and a bottom wall 10, said bottom wall being detachable and normally held in place by screws 11 or other fastening means. The top wall 9 of the head 8 is formed with a central seat 12 and a collar 13 axially alining with a collar 14 of the bottom plate 10 and these collars will provide clearance for a center drill or socket should it be desired to use the same. In the collars 13 and 14 is a bushing 15 and a closure 16, the latter being removed when the former accommodates a center drill or socket.

55 Mounted in the seat 12 is an anti-frictional radial bearing 17 for a center gear 18 which has the upper end of its hub journaled in an opening 19 provided therefor in the top wall of the casing 3. The center gear 18 is mounted on the shank 20 of a tapered adapter 21 extending into a drive spindle 22 journaled in the sleeve member 1, and when a center drill is placed in the collars 13 and 14 the drill may have its connecting member or shank extend into the center gear 18, so that said center gear will serve functionally as a coupling member to permit of power being transmitted direct to the center drill from the drive spindle 21.

Mounted in the top wall of the casing 3 and the top wall 9 of the head 8 are pins 23 provided with bushings 24 of intermediate

gears 25 which mesh with the center gear 18, said intermediate gears being preferably two in number and diametrically opposed, as best shown in Fig. 2. Three intermediate gears 5 may be used for a six spindle drill head and six intermediate gears for a twelve spindle head. Provision is made for oiling the intermediate gears by ports 26 in said gears and the bushings thereof, and the entire interior of the transmission casing 10 may be filled with a suitable lubricant to insure easy running of the transmission mechanism therein.

The top wall 9 of the head 8 has a plurality of large openings 27 with packing 28 in the opening walls, and journaled in said openings are transmission housings 29 which communicate with the casing 3 to receive lubricant therefrom. The transmission 15 housings 29 are retained in the head 8 for adjustment therein by pivot pins 30 having the upper ends thereof seated in the top wall of the casing 3 and the lower ends thereof extending through the housings 29 20 into the bottom plate 10. The pivot pins 30 are axially of the transmission housings 29 so that said housings may be swung about said pins, and rotatable on each pin is a compound gear composed of gears 31 and 32. The gears 31 mesh with the intermediate gears 25 and cooperate with said intermediate gears and the center gear 18 in providing a transmission mechanism within the casing 3, so that power may be transmitted 25 from the adapter 21 through the transmission mechanism to the gears 32 in the housings 29. The compound gears are supported by suitable bushings 33 and lubricant is supplied to the pivot pins 30 through ports 34 30 communicating with the housings 29 and the casing 3.

The transmission housings 29 have offset portions 35 provided with packing 36 and anti-frictional radial bearings 37 for compound gears 45 within the offset portions 35 of the housings 29 and socket members 38 adjustably supported against the bottom plate 10 of the head 8. Each compound gear is in the form of a lower gear 39 having an elongated hub 40 provided with an upper gear 41, said upper gear meshing with the gear 32 in each housing 29. Extending through each compound gear is a suspension or pivot bolt 42 which has its upper end seated on the offset portion 35 of each housing 29 and its lower end extending through an offset portion 43 of the socket member 29, said offset portion containing anti-frictional radial bearings 44 for the gear 39 therein. On the lower end of the suspension or pivot bolt 42 is a nut 45 and by tightening said nut the socket member may be clamped against the bottom plate 10 of the head 8.

With the compound gear and the pivot 60 bolt extending out of the head 8 into the

socket member 38 it is necessary that the bottom plate 10 of the head 8 be provided with segment shaped slots 46, best shown in Fig. 3, said slots being described on arcs having for their centers the pivot pins 30. The slots 46 are suitably spaced apart in the bottom plate 10 so that adjustment of one of the transmission housings 29 will not interfere with adjustment of others.

Journalled in each socket member is a 75 socket 47 supported therein by anti-frictional radial and end thrust bearings 48 and on each socket is a gear wheel 49 meshing with the gear wheel 39 within the offset portion 43 of the socket member. Each socket 80 may be provided with a suitable drill or boring instrumentality.

In addition to the suspension or pivot bolts 42 being employed for clamping the socket members 38 against the head 8 there 85 are clamping members 50 carried by T bolts 51 adjustable in segment shaped grooves 52 in the lower face of the bottom wall 10, said grooves being described on greater arcs than the slots 46 but having the same centers as 90 the arcs of said slot. The clamping members 50 extend under flanges 53 on the upper ends of the socket members 38, as best shown in Fig. 1, and with said clamping members 50 and the nuts 45 loose the socket members 38 95 may be swung about the pivot bolts 42 as axes, such adjustment being independent of the swinging adjustment of the transmission housings 29 within the head 8. Of course, while the clamping members 50 and the nuts 100 45 are loose the transmission housings 29 can be adjusted within the head 8 and by tightening the nuts 45 the pivot bolts 42 will simultaneously clamp the housings 29 and the socket members 38 to the bottom wall 105 10 of the drill head. While the pivot bolts 42 may be depended upon to hold the transmission housings 29 the clamping members 50 are used as additional means to hold the socket members 38.

By reference to Figs. 1 and 3 it will be noted that the sockets 47 may be swung in and out relative to the axis of the adapter 21 and still be driven from said adapter. It is possible to place the sockets 47 in proximity to each other when drilling holes that are close together or by adjusting the transmission housings as far as possible relative to the slots 46 and then swinging the socket members 38 outwardly it is possible to drill 115 120 holes that are very far apart. Furthermore, since the transmission housings and the socket members are adjustable independently of adjacent housings or members it is possible to drill holes that are irregularly 125 spaced and it is this particular kind of work where my improved multiple drill head can be used to an advantage.

Considering other improvements, the drill head 8 has side enlargements 53^a which per- 130

mit of suitable braces being employed in a drilling machine for positively holding the head 8 during any operations, and the enlargements are shaped or of such configuration as to permit of braces being easily used

5 is a conventional form of drilling machine. As there are many types of drilling machines it is necessary that in order for a drilling head to be universal that it be equipped 10 with adapters of various styles permitting of the drilling head being used in connection with any drilling machine. Some of these adapters have been shown in Figs. 5 and 6, and in Fig. 5 the adapter or drive spindle 54 is cylindrical and is journaled in a bushing 15 55 set in a sleeve member 56 which has a detachable flange 57. The center gear 18 is keyed or otherwise mounted on the adapter or drive spindle 54 and an anti-frictional 20 end thrust bearing 58 is installed between the lower end of the sleeve member 56 and a collar 59 on the adapter or spindle 54. This view of the drawing also illustrates how the shank or tang 60 of a center drill may be 25 coupled to the adapter or spindle 54.

In Fig. 6 the drive spindle is designated 61 and is journaled in the sleeve member 62 having its lower end enlarged to afford an enclosure 63 and a flange 64, the enclosure 30 65 accommodating an anti-friction end thrust bearing 65. An adapter 66, similar to the adapter 21, extends into the drive spindle 61 and couples said drive spindle to the center gear 18. In this instance the center gear has 35 an anti-frictional end thrust bearing 67 seated in the top wall of the transmission casing 3.

What I claim is:—

1. In a drill head, a sleeve member, a 40 drive spindle therein an adjustable transmission casing connected to said sleeve member, a head connected to said casing and having a slotted bottom wall, adjustable transmission housings in said head communicating with said casing and adapted to receive lubricant therefrom, adjustable socket members below said head, and having portions thereof extending through the slotted bottom wall of said head, sockets in said 45 50 socket members, means carried by said transmission housings to prevent lubricant from passing from said housing through the slotted bottom wall of said head, and means in said socket members, said transmission housings and casing operated from said drive 55 60 spindle for rotating said sockets.

2. In a drill head having a slotted bottom wall, suspension bolts extending through the slots of said wall, socket members carried

by said bolts against said wall and adapted 60 to be fixed relative to said wall by tightening said bolts, sockets in said socket members, and means in said head and about said suspension bolts for imparting movement to said sockets.

65

3. A drill head as in claim 2, wherein additional means carried by said bottom wall may fix said socket members relative thereto.

4. In a drill head, pivot pins, housings in said head adapted to swing about said 70 pins, said housings having the upper ends thereof open to receive lubricant, suspension bolts carried by said housings, packing about said suspension bolts to prevent leakage of lubricant from said housings, socket members adapted to swing about said bolts, sockets in said socket members, and means about said pins and bolts adapted to impart movement to said sockets.

75

5. A drill head as in claim 4, characterized 80 by said suspension bolts being constructively arranged to simultaneously lock said housings and socket members against movement.

6. In a drill head, axial power transmission means, a transmission housing having 85 centers in defined relation to the axis of the drill head, said transmission housings having offset portions adapted to swing relative to the centers of said housings, socket members having offset portions supported 90 from the offset portions of said housings and constructively arranged to swing relative to the axes of the offset portions, sockets in said socket members and means maintained in position at the centers of said housings and 95 socket members and the offset portions thereof for transmitting power to said sockets from said power transmission means.

7. A drill head having a slotted bottom wall, a pivoted transmission housing in said 100 head and having an offset portion, a socket member outside of the bottom wall of said head and having an offset portion connected through the slot of said bottom wall, to the offset portion of said housing, a socket in 105 said socket member, and power transmission means from said transmission housing to said socket.

8. A drill head as characterized in claim 7, wherein said power transmission means is 110 about the connection between said transmission housing and said socket member.

In testimony whereof I affix my signature in presence of two witnesses.

JOSEPH F. BUHR.
